UNITED STATES PATENT OFFICE.

CARLTON ELMER STONER, OF LONG BEACH, CALIFORNIA.

DECOY.

Application filed February 19, 1925. Serial No. 10,189.

My invention relates to inflated decoys.

While the specific embodiment which I have elected to illustrate my invention is a decoy duck, it is to be understood that the invention is not to be limited to ducks, but may be employed in connection with any other inflated decoy, or the like.

Inflated decoys, as is known to those skilled in the art, comprise essentially a casing or skin usually made of canvas and a rubber bladder or air bag which is so shaped as to fill the casing when inflated to a suitable degree. The air bag is usually inserted into the casing through an opening in the bottom of the body portion of the casing, which is thereafter laced or otherwise closed.

The chief difficulty encountered in making up a decoy of this character is to cause the bladder or air bag properly to fill the head of the shell or casing. This is particularly true with regard to the bill portion which, because of its relatively small and non-circular cross section, presents considerable difficulty, first to the initial introduction of the corresponding parts of the air bag into the casing and next, to maintaining the same in position after inflation and deflation so as to preserve the proper contour of this part of the decoy. The bill is a highly characteristic part of the decoy and it is desirable that the decoy have the proper contour and proportion to cause the same to be as realistic as possible.

I am aware that it is old in the art to pull the air bag into the bill part of the casing by means of a cord, but I find that this structure will not permit the bill to be filled completely, nor to the proper shape, nor will it when inflated give an accurate simulation of the shape of the bill. The cord is usually attached to the end of the air bag by means of a loop of rubber and this prevents the bag from coming quite to the end of the bill part of the casing. Furthermore, the inflation of the bag tends to exert equal pressure in all directions with the result that the bill tends to be circular in cross section and conical in general contour with a flabby, shapeless end, where the air bag does not enter.

Now, according to the present invention I provide a plug in the inside of that part of the bag which forms or fills the bill of the casing. This plug is sufficiently rigid to permit the end of the bag to which it is at-

tached to be thrust into the bill part of the casing and to fill the same completely. It is preferably, although not necessarily, formed of solid rubber and cemented at the front end of the inside of the end of the bag which fills the bill of the casing. It is also preferably so formed at its front end as to give the desired flat shape to that part of the casing which forms the bill.

In addition, it may be so formed as to be pressed past the narrow or constricted part of the casing so that the bill part of the bag will remain in the bill part of the casing.

In addition to the above chief improvement, I have provided other and incidental improvements which will be apparent from the following specification and claims.

Now in order to acquaint those skilled in the art with the manner of constructing and operating a device embodying my invention, I shall describe in connection with the accompanying drawings, a specific embodiment of the same.

In the drawings:

Figure 1 is a side elevational view of a decoy embodying my invention;

Fig. 1^A is a sectional view on plane X—X Fig. 2.

Fig. 2 is a rear elevational view of the same;

Fig. 3 is a top plan view of a portion of the decoy showing the shape of the bill;

Fig. 4 is a fragmentary view of a part of the rubber air bag or bladder before the introduction of the stiffening piece in the bill thereof;

Fig. 5 is a cross sectional view through the bill portion of the casing taken on the line 5—5 of Figs. 1 and 3;

Fig. 6 is a similar cross sectional view on the line 6—6 of Figs. 1 and 3;

Figs. 7 and 8 are side and top plan views, respectively, of a rubber nose or filler for insertion in the middle portion of the air bag, shown in Fig. 4;

Figs. 9 and 10 are sections, respectively, on the lines 9 and 10 of Fig. 8, showing the contour of the bill;

Figs. 11 and 12 are like views showing a modification for making room for the seam in the casing;

Fig. 13 is a sectional view through the front end of the air bag with the rubber bill cemented in place;

Fig. 14 is a horizontal section through the structure shown in Fig. 13;

Fig. 15 is a modified form of bill and air bag embodying my invention;

Fig. 16 is a fragmentary sectional view through the valve for inflating the air bag; and

Fig. 17 is a fragmentary vertical section through a modification showing the bill of a goose decoy having a constriction in a vertical direction.

- 10 In Fig. 1, I have shown a side elevational view of the complete decoy which comprises the outer canvas casing 1. This casing may be made of any suitable material, preferably a canvas cloth formed in two parts or halves, 15 the seam 2 between the same lying in a vertical plane, as indicated in Fig. 2. The canvas casing is adapted to be distended by a suitable rubber air bladder or air bag 3 which has at the rear end a valve portion 20 4 extending out below the tail portion 5 of the casing for inflating the bag. The air bag or bladder 3 is preferably made up of two thin sheets of rubber cemented together at their edges by a lap seam, as indicated 25 in Fig. 4, and this air bag has a head portion 6 which is adapted to fill the head 7 of the casing of the decoy. The head portion 6 has, at its front end, the bill or nose portion 30 8 for filling the corresponding bill or nose portion 8 of the casing.

Now it is highly desirable that the decoy be made to look as life-like and as true to form as is possible. The difficulty with filling the nose or bill portion of the decoy 35 lies in the fact that the front end 8 of the air bag tends to inflate the same to a circular or generally round cross section, whereas the actual duck's bill is of irregular cross section and it should be somewhat of 40 the shape shown in Figs. 5 and 6 at the sections indicated on the corresponding lines of Figs. 1 and 3. That is to say, in Figs. 5 and 6, I have shown sections through the casing, the section shown in Fig. 5 being relatively high and narrow as compared with 45 the section shown in Fig. 6 which is beyond the section of Fig. 5. Now the mere introduction of the projecting portion 8 of the air bladder 3 into the casing would not secure 50 the final shape of the bill of the decoy according to the forms shown in Figs. 5 and 6. Furthermore, the seams 2 have a certain amount of selvage, as indicated at 55 10 in the figures, which in the small cross section afforded in the bill portion of the decoy comprises a noticeable part of the same and affords a real obstacle to securing a nicely shaped bill. In addition, it is desirable in the canvas casing to show a ridge 60 or seam, as indicated at 11, on each side of the bill portion so as to simulate the lower edges of the bill of the bird which the decoy represents.

Now it will be observed, particularly by 65 observation of Fig. 3 and Figs. 5 and 6,

that the intermediate portion of the bill 8, indicated at 12, is relatively restricted in width as compared with the terminal or outer end portion 13 for the definite purpose of assisting in holding the projecting portion 8 of the bladder in the bill portion 9 of the decoy.

I provide inside of the projecting portion a filling member or stud preferably made of soft tough rubber of the shape shown in Figs. 7 and 8, this stud 14 simulating closely the contour in slightly smaller size of the bill of the decoy. It will be apparent that the outer spatulate end of the stud member 14 is wider than the intermediate portion so as to fit the projecting portion 8 of the bladder accurately to the casing and to fit the casing.

The stud member 14 is inserted inside of the air bag 3 in the position shown in Figs. 13 and 14, that is, with the front end of the plug or stud 14 in contact with the front end of the projecting portion 8 and cemented thereto, as indicated at 15.

Now it will be observed that when the air bladder 3 is inserted into the casing 1 through the laced filling opening 16 formed in the bottom part of the casing, the stud 14 may be employed to work the head 6 and projecting portion 8 of the air bag 3 into the corresponding part of the casing and to push the front end of the air bag completely into the front end of the bill portion 9 of the casing.

If desired, the plug member 14 may have a groove 17 at the top and a like groove 18 at the bottom to allow for the selvage of the seam 10 in the bill portion of the duck so that the seam will not be pressed outwardly and form a ridge, as might be the case if no allowance were made on the stud 14.

The stud 14 does not need to fit the complete interior of the bag 3, but I prefer that this stud 14 fit the front end of the bill with sufficient accuracy that after the relatively wide spatulate portion at the front, shown in section in Fig. 10, is pushed past the restricted portion, shown in Fig. 9, there will be a tendency to hold the parts in place due to the friction between the air bag and the canvas casing. The stud 14 need not be of solid rubber; it may be made of sponge rubber, or it may be made hollow, so long as it is sufficiently rigid to permit the nose or bill portion of the air bag to be worked into and pressed to the end of the bill portion of the casing.

In Fig. 15 I have shown a modification in which the head portion 6 of the rubber bag 3 does not extend outward in the shape of the projecting portion 8, shown in Fig. 4, but ends at the point indicated at 20 in Fig. 15, the hollow stud portion 21 being shaped so as to receive the end of the bag 130 and to be cemented thereto, this portion of

the stud 21, which extends beyond the point 20, being accurately shaped to the desired configuration above described and to fit nicely in the bill portion 9 of the canvas casing. I have shown the stud 21 as being hollow and composed of soft tough rubber with sufficient rigidity to permit the same to be pressed by means of the thumb and forefinger into the front end of the casing, 10 as previously described.

The valve 4 comprises a sleeve of soft tough rubber 22 which is cemented at the rear end of the air bag 3 and a sleeve of denser and less elastic rubber, as indicated 15 at 23, is cemented inside of the same to form a valve seat for the valve plug or cork 24, which is preferably formed of relatively stiff rubber. To secure the valve 24 to the body of the decoy so that the same may not 20 be lost, I provide a connection 25 which preferably is a stout flaxen thread inserted as by means of a needle through the body of the plug or valve 24, the thread being preferably dipped in rubber cement before 25 it is thus inserted in the plug 24 and a knot being tied at the inner end of the same, so that the valve plug 24 may be pulled out by means of the string or thread 25. The opposite end of the thread is secured to the 30 tail 5 of the decoy.

In Fig. 17 I have shown a modification namely, the bill of a Canada goose. In this structure, the casing 35 has a constricted portion vertically at 36. The air bag 37 fits into the casing 36 and within the air bag, I provide the plug 38 which is shown as hollow and cemented to the front end of the air bag so as to fill out and form the 40 front end of the bill.

It will be understood that the constriction may be made at any point desired so long as it provides proper configuration of the bill of the decoy. Obviously, instead of ducks and geese, the decoy may simulate 45 any desired bird or animal.

I contemplate in addition to the stud, which I have above described as a means for inserting the inflating bag properly into the casing, the provision of means for tying the air bag to the casing as by means of a loop 26 which is secured to the air bag, as by means of the patches or reinforcements 50 27, 28, which are connected by the integral loop portion 26. A string is preferably 55 secured on the inside of the casing at the point indicated at 30 on Fig. 1, and this string is passed through the loop 26 and internally tied thereto so that after the bladder or air bag is once in place it will 60 tend to remain there. While this loop 26 is shown as being disposed at throat portion of the bag for attachment at the throat of the casing, the loop may be attached at any other suitable point about the head 65 or neck of the air bag and fastened, as by

tying, to the corresponding part of the casing.

In order to steady and properly ballast the decoy I provide a pair of loops 31 which are sewed to the casing 1 at the bottom, each 70 approximately two inches away from the laced opening 16, and I join a weight or plummet 32 to these lugs, either by means of a V-shaped string connection, shown in Fig. 2, or by means of two separate strands 75 of cord 33 running to the weight or plummet 32. I find that the attachment of the weight or plummet at the sides, as I have indicated in Figs. 1 and 2, acts very much like a rudder in steadyng the decoy against so 80 rolling motion. Obviously, the cords 33 may be attached to eyes or otherwise secured to the sides of the casing, although I find the loops 31 are simple and effective means for performing that function. 85

I do not intend to be limited to the details shown or described.

I claim:

1. In a decoy, a casing having a body with a bill portion, an air retaining bag in 90 said casing having a co-operating bill portion for filling the bill portion of the casing and a relatively stiff plug member for thrusting the bill portion of the air bag into the bill portion of the casing. 95

2. In a decoy, a casing having an elongated projection of relatively small diameter, an air retaining bladder for the casing, said bladder having a co-operating projection comprising a relatively stiff plug secured to 100 the bladder adapted to be pushed endwise into the projection of the casing.

3. In a decoy, a casing having an elongated projection of relatively small diameter and irregular cross section, and an air retaining bladder adapted to fill the casing, 105 said bladder having a projecting portion for filling the projection of the casing, and means carried by said bladder for thrusting the projecting portion of the bladder into 110 the projection of the casing.

4. In a decoy, a casing having an elongated projection of relatively small diameter and irregular cross section, the diameter of the projection being greater at the front 115 closed end than at an intermediate portion, and an air retaining bladder having a projecting portion for filling the projection of the casing, said projecting portion having an internal stiffening plug. 120

5. In a decoy, a casing having an elongated projection of relatively small diameter and irregular cross section, the diameter of the projection being greater at the front closed end than at an intermediate portion, 125 and an air retaining bladder having a projecting portion for filling the projection of the casing, said projecting portion having a reinforcement to render it sufficiently rigid to thrust the projecting portion of the air 130

- bag into the projection of the casing, and to provide a relatively enlarged front end which will be held by friction beyond said restricted portion.
5. 6. In a decoy, a casing having an elongated projection of relatively small diameter, an air retaining bladder having a projecting portion for filling the projection of the casing, said projecting portion having sufficient rigidity to permit thrusting the same into the projection of the casing by pressure applied endwise.
10. 7. In a decoy, a casing having an elongated projection of relatively small diameter and irregular cross section, an air retaining bladder having a projecting portion for filling the projection of the casing, and a rubber stud of approximately the desired shape of the decoy projection lying inside the projecting portion of the air bag.
15. 8. In combination, a decoy casing having an elongated projection at the front end thereof, an air retaining bag having a pro-
- jection portion, and a rubber stud secured to the front end of the air bag for filling the projection of the casing, said stud being of sufficient rigidity to permit the same to be thrust endwise into said projection of the casing.
20. 9. In a decoy, a jacket of canvas simulating in color and contour a water bird, said jacket having a bill portion closed at the front end, an inflatable air retaining bag for distending said jacket, said air bag comprising thin sheet rubber and having a co-operating bill portion for entering the closed bill portion of the jacket to distend the bill of the jacket mechanically to the desired contour, said bill portion of the air bag comprising a plug of material rigid enough to retain its desired shape, and permitting it to be thrust endwise into the bill portion of the jacket.

In witness whereof, I hereunto subscribe my name this 16th day of February, 1925.

CARLTON ELMER STONER.
